UNITED STATES PATENT OFFICE.

JAMES W. YATES, OF CINCINNATI, OHIO, ASSIGNOR TO THE CINCINNATI TIME RECORDER COMPANY, OF CINCINNATI, OHIO, A CORPORATION OF OHIO.

TIME RECORDER.

Application filed January 3, 1923. Serial No. 610,521.

My invention relates to time recorders of the type generally known as fully automatic, in that the shifting of the card with relation to the printing mechanism or time wheels, 5 is accomplished entirely by the time mechanism, without any selective act by the operator.

My invention also relates to the use of a fully automatic card tray shift for lateral 10 movements of a card retaining tray, for the "days of the week" shift, and of a cam controlled abutment adjacent the tray as the "in and out" shift.

Among other things it is the object of my 15 invention to accomplish the movement of the card tray by means of the time clock entirely, and to so do this, that the tray is locked in clock actuated position and remains there for a full day without being capable of being 20 forced out of position.

Thus more specifically I move the tray laterally by means of a cam, energized by a pawl, the weight of which is raised during each twenty four hours and then dropped, 25 the cam being so arranged that it acts as a worm, and is therefore self locking. I return the card tray to starting position by a spring, which spring is placed under tension during the entire week.

30 In order to prevent the cam from being revolved in a reverse direction, I provide a pawl and ratchet, and I also provide an overthrow prevention pawl for the operating pawl.

35 I have designed my whole mechanism and scheme of operation in such a way that the least possible strain is given to the clock mechanism.

40 I accomplish my various objects by that certain construction and arrangement of parts to be hereinafter more specifically pointed out and claimed.

In the drawings,

45 Figure 1 is a front elevation of the device, with casing and certain parts omitted, for purposes of clearness.

Figure 2 is a side elevation of the device, showing the operative mechanism for the card tray cam.

50 Figure 3 is an edgewise view of the card tray lever.

Figure 4 is a front elevation of the said lever.

Figure 5 is a detail rear elevation of the cam. 55

Figure 6 is a section taken horizontally through the center of the cam.

Figure 7 is a detail left side elevation, showing the pawl and ratchet.

Figure 8 is a front elevation showing a detail of the cam and operating parts. 60

Figure 9 is a side elevation showing the cam operating parts.

Figure 10 is a plan view of a card as used in my invention. 65

The frame-work parts of the machine are indicated at 1 and the supporting bar for the card tray at 2. The tray comprises a rectangular structure formed of channelled side bars 3, a base bar 4, and a hopper-like mouth 5 70 into which the card is inserted.

Connected to the tray is a link 6, connected to a depending arm or lever 7. This lever, known as the card tray lever, is pivoted to a small bracket 8 at the base of the machine. 75 The lever is bent to provide proper clearance for various mechanism parts, and carries an antifriction roller 9, which is cam operated to move the tray from point to point. A spring 10 is connected to the lower end of the card tray lever and serves to pull it toward an initial position to the left end of its path of movement.

I have shown portions of the time printing mechanism as for example the ribbon 11, the operating handle 12, the time wheels 13, and the ribbon shift bar 14. None of these devices has in its structure any departure from known forms of construction. 85

As a means for operating an abutment in the card tray for positioning an inserted card lengthwise at different hours of the day with relation to the printing wheels, I employ the structure set forth in the patent to Hugh M. Lawton No. 1,253,185, dated January 8, 1918. 90

Thus I have a cam 20, operated by a train of gears from the shaft 21 of the time clock, which cam revolves once every twenty-four hours. Resting on the cam is a yoke 22 having a cross roller 23 resting on the cam. At the forward end of the yoke is a cross bar 24 of sufficient width to include the full path of the card tray. The card tray has a slide therein, as indicated at 25, which serves as an abutment for any card thrust in through the 100 105

hopper of the tray. This slide has a pin 26 thereon, which rests on the cross bar 24 at all times, and this weight is counterbalanced by a spring 27 at the back of the yoke.

5 The construction of the cam is such that during the day there is a rapid movement of the abutment upwardly, while men are likely to be going in or out, and a slow or non-movement when all men are at work.

10 For operating the card tray so that it shall move bodily across the face of the type wheels, thereby making a day of the week shift, I provide a spiral cam member 30 having a groove 31 therein of spiral nature, with a straight line return portion 32, so that when revolving the cam, with the antifriction roller pin on the card tray lever lying in the groove, the tray can be fed across the front of the machine, until the roller comes 20 to the straight portion whereupon the tray will be pulled back to starting position by the spring 10. A slight movement of the cam will impart a large movement to the card tray lever at its upper end if located low enough 25 in the machine.

As mounting means for the cam I provide a horizontal shaft 33, set in roller bearing housings 34, in two interspaced standards 35 at the base of the machine. The cam is 30 then pinned in any desired way to the shaft so as to revolve therewith, and so as to lie in a horizontal plane. The spiral groove on the cam is of one complete turn around the axis thereof including of course the straight portion of the groove. The anti-friction pin on the tray lever cuts down friction, and the operation of the cam, its shaft, and the card tray lever and tray calls for but slight expenditure of energy.

40 When the cam is in any position but with its straight groove portion engaging the card tray pin roller the effect of the spiral is to lock the tray against movement, after the usual principle of locking worm gears. Furthermore I prevent any motion of the cam as 45 a result of trying to force the tray one way or the other to falsify the machine, by a pawl and ratchet to be described.

When the pin roller is in the straight part 50 of the groove, however, the effect is to permit the tray to be moved wherever it is desired so that some additional holding means is required. For the purpose of holding the tray to the left hand end of the cam groove, 55 I provide a small plate 36, screwed down by the screw 37 into the base of the groove so that it can rock, and in a socket in the base of the groove I seat a small spring 38, which bears on the plate and elevates its end. This 60 elevated end of the plate will engage the pin roller and hold it at the desired point.

65 Referring next to the operation of the cam, I show as a preferred means a cam 40, driven around once every twenty four hours by means of the gear train 41, from the clock

time shaft. On bracket 42 on the base of the machine I mount a lever 43, which is pulled by a spring 44 so as to bring its forward end downwardly.

The effect of the spring is to pull upwardly 70 the rear end of the lever, which carries a roller 46, said roller bearing against the surface of the cam. The cam is so shaped that it gradually lowers the rear end of the lever against the spring, and then at the end of 75 twenty four hours, drops the roller off the point 45 on the cam, and permits the spring to pull the lever smartly upward.

This spring action is what directly moves the tray and it may be observed that if the 80 clock fails, for any reason, due to negligence, or in winding or clogging up, to fully elevate the lever and drop it, that this will result from or give rise to a stopping of the clock thereby giving an indication of the fact 85 that something is wrong. If an operator should endeavor to hold the tray against movement when the lever is released under its spring tension this will not stop the clock, which will remain free to run as usual until 90 the tray is released, whereupon the spring will move it over.

The method of revolving the cam carrying shaft includes a ratchet 50 on the shaft, over which plays a pawl 51. This pawl 51 95 is mounted on a rocker 52 on the shaft and free to revolve thereon, this rocker being coupled by a link 53, with the lever 43. A spring 54 is connected to a pin 55 on the pawl and to the rocker, to place spring pressure on the 100 pawl, whereby it will engage the ratchet in the proper direction, and snap over its teeth in the other.

I have shown the ratchet 50 as having seven teeth, and I also provide a ratchet 56, fast on 105 the shaft and having seven rectangular teeth. Of course the number of teeth is variable with the number of times it is desired to have the tray shifted.

A pawl 57 is provided, and mounted on a 110 fixed stud or pin 58 on the machine frame. This pawl is pressed by means of a spring 59 toward the ratchet 56.

The tooth 60 on the pawl engages in the rectangular teeth of its ratchet. The pawl 115 has also a laterally extending head portion 61, which lies in the path of a pin 62 on the operating pawl 51.

The parts described are so arranged that as the cam raises the lever, rocker, and pawl 120 to a position of highest elevation, the pin 62 will pass the extension 61 and take a position above it. As soon as the lever is released, and the spring pulls it down at the forward end, the pin 62 first strikes the pawl 57, out of mesh with the ratchet, then engages the adjacent tooth of the operating ratchet 50 and revolves the cam and shaft. The pin 62 passes the extension 61 in its downward path, so 125 that the pawl 57 engages the surface of its 130

ratchet ready to snap into the next notch, the former notch having been moved away by the action of the operating pawl, prior to release of said pawl 57.

5 It follows that when the operating ratchet and hence the cam have been moved through a distance of one step the pawl 57 will come into engagement and stop not only any further movement of the cam in the driven direction, but also any reverse movement of the cam such as might result by an attempt to jam over the tray.

The nature of the cam groove will be brought into correspondence with the spacing 15 of the cards into columns for days of the week so that each one step of movement of the operating ratchet will move the cam enough to shift the tray laterally one column space. The card printed by my invention 20 will be as shown in Figure 10, with hours printed in vertical columns and days of the week across the card.

Having thus described my invention, what 25 I claim as new and desire to secure by Letters Patent, is:

1. A device for shifting a card tray in time recorders laterally for day to day changes in position comprising a lever connected at one end to the card tray, and at the other to a 30 fixed point, a projection on the lever, a spiral cam adapted to receive said projection and means for operating said cam driven by the time movement of the recorder, and a spring resisting the cam impelled movement of the 35 tray.

2. A device for shifting a card tray in time recorders laterally for day to day changes in position, comprising a lever connected at one end to the card tray, and at the other to a 40 fixed point, a projection on the lever, a spiral cam adapted to receive said projection and means for operating said cam driven by the time movement of the recorder, a spring pulling said tray to a starting position for the 45 first day of the week, and a straight portion in the cam through which portion the lever projection is pulled by the spring, said operating means for the cam comprising a clock driven cam disk and a member engaging the

clock driven cam, and effecting movement of 50 the spiral cam one step for each revolution of the clock driven cam.

3. A device for shifting a card tray in time recorders laterally for day to day changes in position, comprising a lever connected at one 55 end to the card tray, and at the other to a fixed point, a projection on the lever, a spiral cam adapted to receive said projection and means for operating said cam driven by the time movement of the recorder, a spring pulling 60 said tray to a starting position for the first day of the week, and a straight portion in the cam through which portion the lever projection is pulled by the spring, and means in said straight portion to prevent reverse 65 movement of the projection against said spring.

4. In a time recorder in combination with a printing element, a card tray moving cam comprising a body having a spiral groove 70 therein, and a straight return portion, and a spring latch element in the straight portion adapted to prevent movement of a cam engaging projection in any one direction but the starting point of the spiral. 75

5. In a time recorder, a clock driven member, a card tray, an abutment in the card tray, a tray moving member, and a gear train from the clock-operated member adapted to shift the abutment into a variety of positions providing for hours of the day, and another gear train from the clock-operated member adapted to shift the tray moving member once every twenty four hours or multiples thereof, for day or multiple day shifts. 80

6. In a time recorder, having a time movement, the combination of a card tray movable laterally, a projection-carrying member connected to said tray, a cam for engaging said projection, and means energized by the time movement for moving said cam by steps and means for preventing movement of the cam in any direction intermediate said step movements, said cam having a spiral groove with a return straight portion, and a latch 90 to prevent movement of the projection in any but one direction in the groove. 95

JAMES W. YATES.
